AIR DISCHARGE CONDUIT FOR COMBINES

Vernon H. Sietmann, Laurel, Iowa 50141, and Gerald F. Dendel, 236 E. 16th St., Costa Mesa, Calif. 92627

Filed Feb. 24, 1969, Ser. No. 15,862

Term of patent 14 years

Int. Cl. D15—03

U.S. Cl. D40—1

FIG. 1 is a frontal perspective view of an air discharge conduit for combines showing our new design;

FIG. 2 is a front elevational view thereof;

FIG. 3 is a side elevational view thereof as seen from the righthand side of FIG. 2;

FIG. 4 is a rearward elevational view thereof;

FIG. 5 is a top plan view thereof; and

FIG. 6 is a bottom plan view thereof.

We claim:

The ornamental design for an air discharge conduit for combines, substantially as shown.
